(No Model.)

J. CONE.
OSCILLATING STEAM ENGINE.

No. 453,964.

Patented June 9, 1891.

UNITED STATES PATENT OFFICE.

JOHN CONE, OF MARQUETTE, MICHIGAN, ASSIGNOR TO PETER FREI AND NICHOLAS BARTH, OF SAME PLACE.

OSCILLATING STEAM-ENGINE.

SPECIFICATION forming part of Letters Patent No. 453,964, dated June 9, 1891.

Application filed December 22, 1890. Serial No. 375,494. (No model.)

To all whom it may concern:

Be it known that I, JOHN CONE, of Marquette, in the county of Marquette and State of Michigan, have invented a new and useful Improvement in Oscillating Steam-Engines, of which the following is a specification.

My invention consists in an improvement in oscillating steam-engines hereinafter fully described and claimed.

10 Figure 1 is a vertical central section with the piston and piston-rod and crank in elevation. Fig. 2 is a plan view with the piston-rod in section.

K K represent two semicircular casings, 15 each provided with a flange R for connection with the bed-plate, and each provided with a threaded opening and a port for steam or exhaust pipe, (marked P and Q.)

L represents an engine-cylinder containing 20 a piston C and piston-rod M, connected therewith by a nut c. On two opposite sides of the cylinder L are formed wings O, (shown in section in Fig. 1 and in dotted lines in Fig. 2,) which are turned semicircular to fit into 25 the inner surface of casings K K and are preferably countersunk into said casings, as shown in dotted lines at E E, Fig. 2. In these wings O are formed two steam-ports A A, which lead from the two ends of cylinder 30 L and are separated by the abutment A', and two exhaust-passages B B, which lead from the ends of cylinder L and are separated by the abutment B', the abutment A' being substantially the same width as the 35 port P through one casing K and the abutment B' being substantially the same width as the port Q through the other casing K, so that said abutments open and close said openings.

40 H represents a stuffing-box on the end of cylinder L.

T T represent lugs cast on casings K opposite the openings P and Q, and D represents tension-springs, by which said lugs T T are 45 connected, thus holding said casings against the wings O with an adjustable and elastic pressure.

U U represent lugs on the upper side of casings K K, by which said casings are bolted 50 together.

G represents a crank, and E' a wrist-pin,

by which the end of piston-rod M is connected by any suitable form of connection.

Assuming P to be the steam-inlet port, when the engine is on the center, as shown in Fig. 55 1, abutment A' closes the inlet-port P. When the engine is thrown off the center, one of the inlet-ports A connects with the port P, and steam passes to the end of the cylinder with which the port connects. At the same 60 time the opposite exhaust-port B is brought in connection with the exhaust-port Q, and steam is exhausted from that end of the cylinder. As the piston C moves, the cylinder L, with its wings O, is oscillated in one direction 65 for the first half of the stroke and then in the other direction for the second half of the stroke, until finally at the end of the stroke the ports again assume the position shown in Fig. 1, except that the piston C is 70 at the other end of the cylinder. A continued motion of the crank G carries the engine over the center, when steam is admitted to the other inlet-port A and exhausted through the other exhaust-port B and a reverse stroke 75 takes place, thus completing a revolution. The wings O may be turned to accurately fit the interior of the casing K at all points of contact, or for the purpose of diminishing friction may be made to fit closely only near 80 the openings of the inlet and exhaust ports A and B.

What I claim as my invention, and desire to secure by Letters Patent, is—

1. An oscillating engine having a cylinder 85 with semicircular wings on opposite sides thereof, each wing having ports leading from a point near its center to the ends of the cylinder and separated at their outer ends by an abutment, and two semicircular casings 90 adapted to fit said wings closely and each having therein a port adapted to register with the abutment in one of the wings when the engine is on the center, and a spring connection between said casings, substantially as 95 shown and described.

2. In an oscillating engine, the combination of a cylinder having semicircular wings formed on the opposite sides thereof chamfered at their periphery and having steam 100 and exhaust passages formed therein, and two semicircular casings countersunk to receive

the chamfered periphery of said wings and connected by an elastic connection, substantially as shown and described.

3. In an oscillating engine, the combination of a cylinder having semicircular wings formed on the opposite sides thereof, chamfered at their periphery and having steam and exhaust passages formed therein, and two

semicircular casings countersunk to receive the chamfered periphery of said wings and connected by an adjustable elastic connection, substantially as shown and described.

JOHN CONE.
